UNITED STATES PATENT OFFICE.

MORRIS SACHS AND SOLOMON FLIEDERBAUM, OF NEW YORK, N. Y.

MOVING SIGN.

Application filed September 28, 1926. Serial No. 138,228.

Our invention relates to improvements in signs, which are moved by machinery in a series, usually in a straight line, and it consists in the novel features, which are hereinafter described.

One of the objects of our improvement is—to have the mechanism of a moving sign compact, especially in the direction of the thickness or depth of the sign-frame, i. e. the direction, which is at right angles to the plane of the moving sign.

Another object of our improvement is—to have each sign face forwardly all the time while travelling in opposite directions with the series, thereby reducing the number of signs, which are not exposed to view.

A further object of our improvement is to have our moving sign simple, durable and inexpensive.

Other objects and advantages will herein-after appear.

We attain these objects by the mechanism, one form of which is illustrated in the accompanying drawings or by any mechanical equivalent or obvious modification of the same.

In the drawings Fig. 1 is a section on the line 1—1 of Fig. 2,

Fig. 2 is a front elevation of our moving sign.

The middle portion of the sign-frame is shown as broken away in both Figs. 1 and 2.

Fig. 3 is a section on the line 3—3 of Fig. 4.

Fig. 4 is a front elevation of one of the sign pockets.

Fig. 5 is a fragmentary top view or plan of our moving sign, showing the placement spring, which is hereinafter described, in its forward position, and showing the sign pockets in a different phase of motion than in Fig. 2.

Like numerals refer to like parts throughout the several views.

11 designates a sign frame which may be built up of longitudinal channels 12 and 13, shown in Fig. 2, and end channels 14, shown in Fig. 1.

Vertical shafts 15 and 16 are shown as revolvably mounted on said frame 11; the bearings for said shafts are omitted in the drawings, for the sake of clearness.

Sprocket wheels 17 and 18 are secured to said shafts 15 and 16 respectively, to mesh with an endless chain 19, which is shown in

Fig. 1 and is omitted in Fig. 5, for the sake of clearness.

As shown in the drawings, the chain 19 is arranged to travel from right to left at the front of the sign and return from left to right at the rear of the sign.

The shaft 15 is shown as having mounted at the upper end thereof a spur gear 20, which is one of a train of gears for transmitting motion to said shaft 15 from a suitable motor or line shaft.

Sign pockets 21 are shown in Figs. 1, 3 and 5 as having each thereon two pins or projections 22 and 23: one pin 22 on the front thereof and one pin 23 on the rear thereof.

The pins 22 are engaged by the part of the chain 19, which travels at the front of the sign, and the pins 23 are engaged by the part of the chain 19, which travels at the rear of the sign.

Guide bars 24 and 25 are secured to the channels 12 and 13 respectively, and serve to keep the series of sign-pockets 21 at the front of the sign separated from the series of pockets 21 at the rear of the sign and to keep said pockets 21 in engagement with the chain 19.

The pins 22 of the series of pockets 21 at the rear of the sign and the pins 23 of the series of pockets at the front of the sign slide on the guide bar 24.

The frame 11 has secured thereto at the front thereof cover plates 26 and 27 to shield from view the sprockets 17 and 18, also the extreme positions of the pockets 21, and, at the rear thereof, lug plates 28 and 29, which have thereon openings 30, for connecting the sign to any vertical structures, such as walls or posts of buildings.

Placement springs 31 and 32 are provided, to move each sign pocket 21 from the front series to the rear series and vice versa, as said pocket reaches the end of the series, thereby disengaging from the chain 19 one of the pins 22 or 23 on said pocket and engaging the other pin.

The placement spring 32 is shown in Fig. 1 as secured by means of a rivet or screw to the lug strip 29 interiorly of the frame 11, and the spring 31 is similarly secured to a short strip 33, which may be secured to the flange of the channel 12 by any suitable fastenings, which are omitted in the drawings for the sake of clearness.

5 The placement spring 32 is shown in Fig. 5 in its forward position after having moved one of said pockets 21 from the series of pockets at the rear of the signs to the series 5 at the front of the signs; the pin 23 of this pocket has been disengaged by said spring 32 from the rear part of the chain 19 and the pin 22 thrown into engagement with the front part of said chain.

10 The guide bars 24 and 25 are shown as shorter than said series of pockets 21, thereby leaving room for each pocket 21 at the end of each series to be moved by said springs 31 and 32 from the front to the rear of the 15 sign-frame and vice versa.

The sign pockets 21 are shown in Fig. 3 as having therein room for signs or advertisements, which are designated in Fig. 2 by the letters A, B, C, D, E, and F.

20 An opening 34 is provided in the front wall of each sign pocket 21 for said signs or advertisements to be displayed there-through.

25 A door 35 is shown in Fig. 2 as covering an opening in the top of the channel 13 of the frame 11, for readily removing signs or advertisements from the pockets 21 and for inserting said signs thereinto.

30 The placement springs 31 and 32 are shown as sinusoidal in shape; but they may also have any other shape, if desired.

35 Many other changes may be made in the details of our moving signs without departing from the main scope of our invention, and parts of our invention may be used without other parts.

We do not, therefore, restrict ourselves to the details as shown in the drawings, but we intend to include also all mechanical 40 equivalents and obvious modifications of the same within the scope of our invention.

Wherever the term "moving sign" is used in the specification and claims, it is meant to designate a series or series of moving signs.

45 We claim as our invention and desire to secure by Letters Patent:

1. In a moving sign an endless flexible member having therein a front part and a rear part, a means for moving the same, two series of sign pockets encompassed by said member, one of said series being engaged by said front part, interiorly of said member, the other of said series of sign pockets being engaged by said rear part, interiorly 50 of said member, and a means for moving each sign pocket, as it reaches the end of its series, in a direction transversely to the plane of said sign, thereby disengaging said pocket from one of said parts and bringing it into engagement with the other part.

55 2. In a moving sign an endless flexible member having therein a front part and a rear part, a means for moving the same, two series of sign pockets encompassed by said member, one of said series being engaged

by said front part interiorly of said member, the other of said series of sign pockets being engaged by said rear part, interiorly of said member, a guide bar placed intermediate of said two series in sliding contact 70 with said pockets, to guide the latter in a straight line; and a means for moving each sign pocket, as it passes the end of said guide bar and reaches the end of its series, in a direction transversely to the plane of 75 said sign, thereby disengaging said pocket from one of said parts and bringing it into engagement with the other part.

3. In a moving sign an endless flexible member having therein a front part and a rear part, a means for moving the same, two series of sign pockets encompassed by said member, one of said series being engaged by said front part interiorly of said member, the other of said series of sign pockets being engaged by said rear part, interiorly of said member, and a placement spring at each end of the sign connected to the front and rear thereof respectively for moving each sign pocket, as it reaches the end of its series, in a direction transversely to the plane of said sign, thereby disengaging said pockets from one of said parts and bringing it into engagement with the other part.

4. In a moving sign an endless flexible member having therein a front part and a rear part, a means for moving the same, two series of sign pockets encompassed by said member, one of said series being adjacent to each of said parts interiorly of said member, a means for detachably engaging said pockets to each of said parts in turn and a means for moving each sign pocket, as it reaches the end of its series, in a direction transversely to the plane of said sign, thereby disengaging said pocket from one of said parts and bringing it into engagement with the other part.

5. In a moving sign an endless flexible member having therein a front part and a rear part, a means for moving the same, two series of sign pockets encompassed by said member, one of said series being adjacent to each of said parts interiorly of said member, pins on the fronts and rears of said pockets in engagement alternately with said front part and with said rear part and a means for moving each sign pocket, as it reaches the end of its series, in a direction transversely thereto, thereby disengaging said pocket from one of said parts and bringing it into engagement with the other part.

6. In a moving sign a frame, a pair of wheels, pivotally connected thereto, an endless flexible member in engagement with said wheels, said member having therein a front part and a rear part, a series of sign pockets in engagement with said front part, a series of sign pockets in engagement with

said rear part, both of said series being encompassed by said member, a means for moving said member, a guide bar, situated between said two series of pockets, to keep them in engagement with said parts, the ends of said bars and said wheels having a space therebetween, and a means for transferring said pockets from the end of each series through said spaces to the other series during the motion thereof.

7. In a moving sign a frame, wheels, pivotally connected thereto, an endless flexible member in engagement with said wheels, said member having therein a front part and a rear part, a series of sign pockets, having thereon front and rear projections, in engagement with said front part by means of

said front projections, a series of sign pockets, having thereon front and rear projections, in engagement with said rear part 20 by means of said rear projections thereof, both of said series being encompassed by said member, a means for moving said member, a guide bar situated between said two series and under the unengaged projections of said pockets, to keep said pockets in engagement with said parts, the ends of said bar and said wheels having a space therebetween, and a means for transferring the said pockets from the ends of each series 25 through said spaces to the other series during the motion thereof.
